UNITED STATES PATENT OFFICE.

AUGUST J. KREUZKAMP, OF CHICAGO, ILLINOIS, ASSIGNOR TO THE ENGLANDER SPRING BED COMPANY, OF BROOKLYN, NEW YORK, A CORPORATION OF NEW YORK.

SLIDING CONVERTIBLE BED.

1,413,595.

Specification of Letters Patent. Patented Apr. 25, 1922.

Application filed June 8, 1921. Serial No. 475,875.

To all whom it may concern:

Be it known that I, AUGUST J. KREUZKAMP, a citizen of the United States, residing at Chicago, in the county of Cook and 5 State of Illinois, have invented certain new and useful Improvements in Sliding Convertible Beds, of which the following is a specification.

This invention relates to beds, an object 10 thereof being to provide a three-section sliding convertible bed comprising a main bed frame and a pair of sliding bed sections shiftable relatively thereto to form a full length bed transverse of the length of the 15 individual sections.

A further object is to provide a three-section sliding convertible bed wherein one 20 of the sliding sections has a non-closed compartment formed from the framework thereof for the reception of a mattress, the construction being such as to provide a convertible bed of this type, which will be efficient, cheap, durable and practicable in construction.

25 A further object of this invention is to provide a bed of the sliding convertible type, one of the sliding sections thereof having a mattress compartment formed as a part of the framework, and located as near as possible to the top of the mattress, a portion of 30 the mattress being constructed to swing rearwardly thereby to permit access to the compartment for the removal of the mattress, and a main section provided with a sliding 35 compartment shiftable at right angles to the movement of the mattress compartment. Thus the construction is such as to result in a cheap, durable and serviceable bed structure adapted for a variety of purposes 40 and at the same time combining utility, convenience and effectiveness.

Other objects of this invention will appear in the following description thereof, reference being had to the accompanying 45 drawings forming a part of this specification, wherein like reference characters indicate corresponding parts in the several views, and wherein Fig. 1 is a perspective view of one embodiment of my improved bed structure; Fig. 2 is a perspective view of another embodiment thereof; Fig. 3 is a perspective view of a further embodiment thereof; Fig. 4 is a perspective view of the struc-

ture illustrated in Fig. 3 showing the mattresses removed and the sliding receptacle 55 in its open position; Fig. 5 is a side elevation partly in section illustrating the embodiment of Fig. 1; Fig. 6 is a side elevation partly in section illustrating the embodiment of Fig. 2; and Fig. 7 is a side elevation of the 60 embodiment illustrated in Figs. 3 and 4.

The present improved bed structure comprises in general a main bed section A, an intermediate sliding section B carried thereby and shiftable relatively thereto, an outer 65 sliding section C carried by the intermediate sliding section and shiftable relatively thereto, and a sliding storage receptacle carried by the side or tie bars of the main section and shiftable beneath the sliding sections 70 and at right angles to the movement thereof.

It has been found in practice that when the bed is in its closed position, it is impracticable to use a single mattress foldable twice upon the main section. The disadvantage of this resides in the fact that the day bed thus formed, having three layers of mattress, is too high from the floor for practical use, hence it is necessary to provide suitable storage space for the mattress of the third 80 sliding section, but at the same time to provide as cheap and efficient a construction as possible. In the present instance therefore, the outer sliding section is provided with a compartment formed largely from the framework of the section and a portion of the spring mattress is hinged to swing rearwardly and permit access to the compartment. Thus, as it will be seen, this compartment is inexpensively formed from the 85 framework, thus obviating any unnecessary or material modification or re-organization of the bed, is conveniently located near the top of the bed, and is so constructed as to provide desirable ventilation for the mattress.

The main and sliding sections of this improved sliding convertible bed may of course be of any preferred construction, in the present instance the same being illustrated by way of example. This bed comprises a main bed section A having end frames 10 provided with the usual supporting legs 11 and a metallic or spring fabric 12 stretched between the end frames. An 100 intermediate sliding bed section B is sup-

ported or carried by the main bed section and comprises end frames 13 having stretched between the same a suitable metallic or spring mattress 14. The end frames 5 13 are provided at one side with supporting legs 15 and at the opposite side with a pair of depending members 16. Side, cross, or spacing bars 18, preferably of angle iron construction, are connected to the legs 11 at 10 a suitable distance below the spring mattress 12 and end spacing bars 17 also of angle iron construction, are connected thereto and to the legs 11, and the horizontal flanges thereof are adapted to form tracks 15 or ways for the depending members 16 of the intermediate section, thereby supporting the same for shiftable movement.

An outer sliding section C is carried by the intermediate section and is adapted to 20 have a shiftable movement relatively thereto. This section comprises end frames 19 having at the outer side thereof depending members 22 and at the inner side thereof depending members 21. Side spacing bars 25 29, preferably of angle iron construction, are connected to the depending members 21 and 22, and supporting legs 23 are connected to the outer side bar 29 and depending members 22, braces 22^a being provided for 30 the purposes of stability and rigidity. The intermediate section B is provided with side spacing bars 24^a and connected thereto at the ends are cross bars 24 preferably of angle iron construction. The horizontal flanges of the end bars 24 are adapted 35 to form ways or tracks for the depending members 21, the outer section thereby having a shiftable movement relatively to the intermediate section and between the end 40 bars 24 and the mattress fabric 14.

In order to provide convenient and accessible storage space for the mattress of the outer sliding section spacing members 25 preferably in the form of slats, are connected at intervals to the side spacing bars 29, the members 25 being spaced from one another, thereby to form an open and ventilated compartment 26. It will be seen that this compartment is formed by the 50 side bars of the mattress section and is located between the same and the mattress fabric.

A portion of the mattress fabric 20 of the outer sliding section is provided at each 55 end with angle bars 27, preferably of less length than the end frames 19, and these bars are pivoted as at 28 to the end frames 19, preferably intermediate the ends and at the inner sides thereof. Connected in any 60 suitable manner to the members 27 is a tie bar 28^a and a side rail 45. Thus this portion of the mattress fabric 20 of the outer sliding section may be elevated as illustrated in dotted lines in Fig. 7, merely by grasping 65 the side rail 45 and swinging the mattress

rearwardly on the pivots 28, and as a result access is permitted to the mattress compartment 26 for insertion or removal of the mattress.

As illustrated in Figs. 1 and 5, the main 70 bed section A comprises a housing framework 30, and a suitable back and arms 31 and 32 respectively formed as part of the framework. A part of the framework 33 forming a front board is connected in any 75 suitable manner to the outer sliding section, and is adapted, upon shifting the sections to their closed and housed position within the framework, to form an ornamental closure for the front of the framework. 80

The type of bed structure illustrated in Figs. 2 and 6 comprises a main bed section A having ornamental end frames 34 and 35, the construction otherwise being substantially the same as hereinbefore described. 85

In order that the intermediate section B and the outer section C may be shifted simultaneously from their position within the housing framework of the main section A suitable automatic locking means is provided to lock the sections together. Thus in opening the bed structure, sections B and C will be shifted as a unit to the full open position of the intermediate section B; thereupon the locking means may be released and the section C shifted to its open position independently of the section B. Hence, the outer and intermediate sections, as desired for the particular use of the bed, are constructed to slide together when desired, thus facilitating the operation of the parts. This locking means comprises a suitable locking spring 36 attached at 37 to the top rails 13 of the section B and having a lug projecting through an opening in the 95 rail and adapted upon closing the sections B and C together to project into an opening or detent 38 formed in the end rails 19 of the section C. The sections are disengaged by pulling the spring outward to withdraw 100 the lugs from the notches or detent 38. 110

A suitable stuffed mattress 40 for the sections A and B is provided, and a stuffed mattress 41 is also provided for the outer sliding section C. Thus, when the bed is 115 used as a day bed, the mattress 41 will be housed within the open compartment 26, such compartment having substantially the same length as the length of the section, thereby to readily house the mattress therein. 120

Suitable tie bars 46, 47, and 48 are connected to the supported legs of the various sections. Referring to Figs. 5 to 7 inclusive, it will be seen that the tie bars 48 are of angle iron construction and the horizontal 125 flanges 49 are adapted to form supporting ways or tracks for the storage receptacle 50, the same being located beneath the ways or tracks 17 and hence beneath the compartment 26 in the closed position of the sec- 130

tions. The supporting legs are provided with suitable rollers 33^a to facilitate movement of the sections and the compartment 26 is provided with end bars or slats 51 to prevent endwise movement of the mattress therein. It will be seen that the mattress storage compartment 26 is formed as an integral part of the framework, thus eliminating considerable expense in construction. Furthermore this compartment, which is open to permit ventilation of the mattress, is the same length as the section G. It will also be seen that the sliding compartment 50 and the compartment 26 in the closed position of the bed are located one above the other, one having a shiftable movement at right angles to the movement of the other. As already seen, the compartment 26 is provided with means for permitting access to the interior thereof for the removal of the mattress, which means comprises a hinged mattress fabric adapted to be swung upwardly and rearwardly relative to the remainder of the mattress.

It will be particularly seen therefore that as the result of the improved construction, wherein a main section and a pair of sliding sections are provided, each sliding section being shiftable between the side bars and the mattress fabric of a companion section, a full length bed adapted to be slept upon transverse of the length of the individual sections is provided. Hence, the necessity of constructing the main section of sufficient length to be slept upon in the direction of its length is eliminated, as in the case of two-section beds of this type heretofore constructed and the main section may be constructed of any length desired (see Fig. 2) without in the least impairing its utility or use as a full length bed as upon converting or opening the bed the combined width of the three sections is sufficient to enable the same to be comfortably slept upon transverse of the sections or in other words, in the direction of the width or shiftable movement of the individual sections.

Although I have described my invention in its preferred form, it is to be understood that I do not limit myself to the construction herein shown and described, except in so far as defined in the claims and embraced within the scope thereof.

I claim as my invention:

1. A convertible bed comprising a main section and a pair of sliding sections shiftable relatively to each other, and to the main section, a pair of said sections having each a compartment thereunder, one compartment located above the other when the sections are closed.

2. A convertible bed comprising a plurality of shiftable bed sections, a pair of said sections having each a compartment thereunder, one compartment being located

above the other when the shiftable sections are closed, one of said compartments being accessible when the bed is closed and both of said compartments being accessible when the bed is open.

3. A sliding convertible bed structure comprising a main section, intermediate and outer sections shiftable relatively to the main section and adapted to be housed thereunder, one of the sections having a mattress compartment formed as part of the framework thereof, the main section having a sliding compartment shiftable upon part of the framework thereof, said mattress compartment in a closed position of the bed being located above the sliding compartment, and one having a shiftable movement at right angles to the movement of the other.

4. A bed structure comprising a main bed section and a pair of sliding sections shiftable relatively thereto to form when opened a full length bed transversely of the length of the individual sections, said bed in closed position having a pair of compartments located one above the other.

5. A bed structure comprising a main bed section, a sliding section shiftable relatively thereto and having depending members, spacing bars connected thereto, spaced members connected to said spacing bars thereby to form an open compartment between the spacing bars and the mattress fabric, and means for permitting access to said compartment, said means comprising a mattress fabric having a portion thereof hinged for swinging movement, said main section having a sliding compartment located below the mattress compartment when the bed is closed, and having a shiftable movement transverse to the movement of said other compartment.

6. A bed structure comprising a main bed section and a pair of sliding sections shiftable relatively thereto and beneath the mattress fabric thereof to form when opened a full length bed transversely of the length of the individual sections, said bed structure having compartment means adapted to occupy in a closed position of the sections substantially the major portion of the space beneath the main mattress fabric.

7. A bed structure comprising a plurality of bed sections one shiftable relatively to another, and one adapted in closed position to be housed beneath the fabric of another, said bed having compartment means adapted to occupy in closed position of the sections substantially the major portion of the space beneath the several mattress fabrics.

8. A sliding convertible bed structure comprising a main bed section, a sliding section carried thereby and adapted to be housed thereunder, said sliding section having a mattress compartment formed as part of the framework and of substantially the same length thereof, and said main section having

a sliding compartment shiftable upon a part of the framework and located below the mattress compartment.

9. A sliding convertible bed structure comprising a main bed section, a sliding section carried thereby and adapted to be housed thereunder, said sliding section having a mattress compartment formed as part of the framework and of substantially the same 10 length thereof, said main section having a sliding compartment shiftable upon a part of the framework and located below the mattress compartment, and one of said compartments having a shiftable movement substantially 15 at right angles to the movement of the other.

10. A sliding convertible bed structure comprising a main section, intermediate and outer sections shiftable relatively to the main 20 section and adapted to be housed thereunder, one of the sections having a mattress compartment formed as part of the framework thereof, the main section having a sliding compartment shiftable upon part of the 25 framework thereof, and means for automatically locking the outer and intermediate sections whereby the same may be shifted simultaneously to an open position and prior to the independent movement of 30 the outer section relatively to the intermediate section.

11. A sliding convertible bed structure comprising a main section, an intermediate section carried thereby for shiftable movement, an outer section carried by the intermediate section for shiftable movement, and spring controlled means for locking said outer and intermediate sections together whereby the same may be shifted together 40 to an open position prior to the release of said locking means and the independent movement of the outer section relatively to the intermediate section.

12. A bed structure comprising a main 45 bed section and a pair of sections shiftable

relatively thereto, said sections each having a mattress fabric, the outer sliding section having depending members, side bars connected to said members, spaced cross bars connected to the side bars thereby to form 50 an open compartment between the side bars and the mattress fabric, and means for automatically locking the outer and intermediate sections whereby the same may be shifted simultaneously to an open position and 55 prior to the independent movement of the outer section relatively to the intermediate section.

13. A convertible bed structure comprising a plurality of shiftable bed sections, said structure having a pair of compartments located one above the other when the shiftable sections are closed, one of said compartments being accessible when the bed is closed and both of said compartments being accessible 60 when the bed is open.

14. A bed structure comprising a plurality of bed sections, one slideable relatively to another and one adapted in closed position to be housed beneath the fabric of another one of said sections having a compartment thereunder, and a companion section having a sliding movement transverse thereto.

15. A convertible bed structure comprising 75 a main spring mattress section and a pair of independent spring mattress sections, each of said sections comprising a permanently stretched spring fabric, supporting means, and lengthwise extending side bars, 80 the spring fabric of one section being shiftable between the side bar and spring fabric of a companion section, said entire sections being shiftable one relatively to another to form when opened a full length bed transversely of the length of the individual sections.

Signed at Chicago, Illinois, this 3rd day of June, 1921.

AUGUST J. KREUZKAMP.
